SKIRT HANGER

John Ambrosino and Morris Pascale,
Flushing, N. Y.

Application October 22, 1949, Serial No. 123,012

3 Claims. (Cl. 223—95)

1

This invention relates to skirt hangers of the general scissor type.

In the forms heretofore proposed certain inherent defects have prevented their utilization in manufacturing skirt establishments and in household uses.

This invention has for its object to provide a skirt hanger which is free from the prevalent objections, and to provide a skirt hanger which accommodates itself readily to the various sizes of skirts, without leaving clipper marks, and which so holds the skirts as to remove wrinkles therein, and keep the skirts in pressed form, and which may also be used to support a jacket belonging to the skirt, so that the entire ladies' suit may be supported in proper hanging position.

The invention consists of two integral skirt supporting portions, each essentially of concave shape and each with a contiguous end which is adapted to enter the waist part of the skirt in a manner that one end of the concave part abuts against the inner part of said waist portion, and that part of said waist portion rests against the lowermost part of said concave portion where the concave portion merges into the end part. This concave curve enables the skirt hanger to adapt itself in a proper skirt hanging position against any size skirt. Combined with this novel skirt engaging portion, are jacket supporting members pivoted to each other and held in spread out position by a spring disposed between said members, said members extending beyond the pivot connection, into hand gripping portions of a special shape enabling easy manipulation, one of the same having a hook to engage a horizontal supporting bar. One of the essential features of the invention is to so relate the concave parts, to the pivoted members, so that at any position of the concave parts, the lower end thereof always supports a skirt, no matter what its size.

The invention will be further described, an embodiment of the same will be shown in the drawings, and the invention will be finally pointed out in the claims.

In the accompanying drawings,

Fig. 1 is a front view of the improved skirt hanger, in fully expanded position as when in use with a skirt;

Fig. 2 is a front view of the skirt hanger in spring compressed position, for a small sized skirt, yet able to support the skirt;

Figs. 3 and 4 are diagrammatic drawings of Figs. 1 and 2, showing the concave portion form-

ing a barrier so that the largest and smallest skirts are suspended and held against slipping off.

Similar characters of reference indicate the same parts throughout the various views.

5 Referring to the drawings, the usual hook 1 is adapted to be applied to a horizontal supporting bar, as known. The hook 1 has one end continuing into an inwardly bent portion 1a, and then into a short straight portion 3, which continues into a bend forming an obtuse angle, after which it is connected with a pivot connection 4, and continues in the straight part 7, to form a jacket support, to a concave part 10, ending in a convex part 10a.

10 15 The other member has a convex part 2, and continues to the aforesaid pivot connection 4, and beyond the same, to the jacket hanger part 8, which terminates in the concave part 11, and its contiguous convex part 11a.

20 25 30 A coiled spring 9 has its free ends pivoted to the hanger, one end pivoted to the arm 7 at 5, and the other end pivoted to the arm 8, at 6, a convolution 9a being centrally disposed to the legs 5a and 6a of said spring 9. The spring 9 has an inherent tension to move the arms 7 and 8 to spread out position while they move on the pivot connection 4. The spring 9 is shown in compressed condition in Fig. 2, and in almost entirely extended position in Fig. 1.

35 40 45 The important feature of the described structure is in the depending concave parts 10 and 11, which are substantially perpendicular when the hanger is in use.

As shown in Fig. 1, the ladies skirt 15 has a waistband hem 16, which is usually slightly conical, flaring downwardly, and the function of the concave part is to have the lower end abut against the inside of the waistband end of the skirt at its lowermost portion, so that the tapering part of the waistband rests on the concave part of the hanger contiguous to the convex part. By this special shape, the concave part properly engages the skirt and hangs it in proper position, so that distortion of the skirt is avoided, and by such proper hanging wrinkles may be removed, keeping the skirt in pressed form, by the weight of the skirt.

50 55 The hanger as shown in Fig. 2 may readily be inserted into a skirt top opening, and allowed to expand until the waistband of the skirt is engaged and pressed outwardly at its diametrically opposite parts.

The concave portions engage the waistband part of the skirt and the latter hugs a portion of the concave above its barrier end.

It is important that the concave part is so disposed that it always remains a concave part in respect to any waistband, that is to say, that at no position of the hanger can the concave part take a position from which the skirt can slip off. There must always be a part of the concave part, namely the lowermost part, which acts as a barrier to a vertical descent of a skirt. It will be noted that this is true for the two extreme positions shown in Figures 1 and 2, and that being so, any intermediate position must embody the same rule of action.

The diagrammatic drawings in Figs. 3 and 4 show parallel verticals 20 and 21, the vertical 20 being tangent to the body of the concave part 10 and the parallel vertical 21 passing through the lowermost end of the concave part 10. The lowermost end of the concave curve 22 always extends horizontally a sufficient amount to act as a barrier impeding the slipping off of the skirt in a downward vertical direction. Thus, the lower end 22 of the concave part 10 always acts as a seat for a skirt. This relatively small barrier portion has the advantage that a skirt may be readily slipped off, which is an important factor in merchandizing, and, of course, may be as readily suspended by the mere bringing together of the hand grip portions 1 and 2, compressing the spring for entrance of the hanger to the skirt.

The gripping portions 2 and 3 are so arranged that they may be easily manipulated, while the hanger is suspended by its hook 1, preparatory to application to a skirt. Or, when it is desired to remove a skirt, while the hanger is supported by the hook, the jacket remaining in position on the hanger, the gripping portions 2 and 3 may be pressed against each other to remove the hanger from the skirt. Also, it is usual to receive skirts from a skirt manufacturer and a jacket from a jacket manufacturer, and thus this hanger serves to hold one or the other until the suit is completely supported by the improved hanger, the compactly arranged gripping portions 2 and 3 facilitating this assembly.

We wish it to be understood that we do not desire to be limited to the exact details of construction shown and described, for obvious modifications will occur to a person skilled in the art.

We claim:

1. In a skirt hanger, having hanger members, joined by a pivot connection, means for moving said members, one of said members having a supporting hook, and a spring for holding said members in normally distant position to the extent of its spring action, the combination of vertically depending members, one integral with each hanger member, and each having an inwardly extending convex portion presenting an outward concave portion for the reception of a skirt at its waistband portion, each of said concave portions at its horizontally deepest part being tangent to a vertical plane and the lowermost end of each of said concave portions being in a second vertical plane parallel with and spaced outwardly of said first vertical plane tangent to the deepest part, said lowermost end providing a barrier against the vertical descent of the skirt waistband portion to hold the waistband portion on said concave portion, whereby said waistband portion is suspended with the waistband in its normal position.

2. The structure of claim 1, in which the hanger members are downwardly inclined diverging away from the pivot connection to form a triangular shaped hanger for jackets.

3. The structure of claim 1, in which the parts above the pivot connection extend away from each and then in vertical parallelism, one being shorter than the other, with said hook on the longer one, and adapted to be moved towards each other to a downwardly divergent inclined position in proximity to each other, whereby the hanger members are brought to proximate position against the action of the spring.

JOHN AMBROSINO.
